UNITED STATES PATENT OFFICE.

MICHAEL JOSEPH HAGER, OF DENMARK, WISCONSIN.

FEED-RACK FOR CALVES.

1,172,985.

Specification of Letters Patent. Patented Feb. 22, 1916.

Application filed November 26, 1915. Serial No. 63,456.

To all whom it may concern:

Be it known that I, MICHAEL J. HAGER, a citizen of the United States, and a resident of Denmark, in the county of Brown and State of Wisconsin, have invented a certain new and useful Improvement in Feed-Racks for Calves, of which the following is a specification.

One of the principal objects of my invention is to provide an improved feeding rack for use particularly in feeding young calves, in which a plurality of stanchions is provided having each associated therewith a drinking bowl, the bowls being separated by partitions, whereby the animals in feeding will be practically isolated from each other and will thus be prevented from interfering one with another in any manner during the feeding process.

20 A further object of the invention is to provide an improved device of the class described in which the movable stanchions may if desired be simultaneously operated through the medium of a sliding bar, and 25 may if desired be operated each independently of the others, so that a large or small number of animals may be conveniently and readily handled.

A further object of the invention is to 30 provide an improved feeding rack which is extremely sanitary, may be readily cleaned and renovated, and one which may be moved from place to place to suit the convenience and purposes of the user.

35 Another object of the invention is to provide an improved feed rack of the class described which will be extremely simple, durable, efficient in operation, and inexpensive to manufacture.

40 With these and other objects in view which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a view in elevation of 50 a feed rack constructed according to my invention. Fig. 2 represents a top plan view thereof. Fig. 3 represents a fragmentary view in perspective of the rack. Fig. 4 represents a view in section taken 55 vertically and transversely on the plane indicated by the line 4—4 of Fig. 1. Fig. 5

represents a view taken vertically and longitudinally on the plane indicated by the line 5—5 of Fig. 2.

In carrying out my invention I provide 60 a feed rack including a pair of lower bars or beams 5, mounted upon spaced skids 6 and braced thereto as at 7, said beams 5 spanning and having secured thereto the lower ends of spaced vertical stationary 65 stanchions 8. The stanchions 8 are secured adjacent to their upper ends between the longitudinally extending upper bars 9.

The stanchions 8 are rounded along one edge at 10 to coact with the rounded edges 70 11 of movable stanchions 12 in engaging the calves' necks between them. The stanchions 12 are arranged each between a pair of stanchions 8, and at their lower ends are pivoted upon pins 13 carried by the 75 lower beams 5. These stanchions 12 may be swung upon their pivots toward and away from the stanchions 8. In order to limit the movement of the stanchions 12 toward the stanchions 8, the stop pins 14 80 are provided, and are mounted through the upper bars 9.

The partitions 15 are each supported by one of the stationary stanchions 8, being secured at its rear edge along the square 85 edge of the stanchion by means of suitable fastenings 16. The partition increases in width downwardly, and has its outer edge turned as at 17 upon a stout wire 18. The upper end of the latter emerges from the 90 turned portion 17 and is provided with an eye 19 engaged by a bolt or pin 20, which passes through the bars 9 and stanchion 8 and serves to secure them in place relatively to each other.

95 Arranged between each pair of partitions 15 and equally spaced from the stationary and movable stanchions occurring between each pair, is a feeding or drinking bowl 21. These bowls are each supported in a ring 100 22 formed by a bowl support in the nature of a channel iron doubled upon itself and having its two portions bent outwardly at spaced intervals to form the rings 22. The portions of the angle iron lying between the 105 rings are spaced apart by blocks 23 to which said portions are secured by rivets or other suitable means 24, and said blocks each support a bolt 25 having a hooked upper end 26 which engages through an opening in one 110 of the partitions 15 adjacent the lower end of the latter, whereby to hook over the wire

18 in the manner indicated in Fig. 5. In this manner the partitions support the bowl support and feeding bowls.

Slidably supported upon the upper ends 5 of the stationary stanchions 8, is a sliding bar 27. This bar is guided through substantially inverted U-shaped straps 28 secured at intervals on the device to the upper ends of certain stanchions 8. Arranged centrally 10 upon the slide bar 27 is a lever 29 of substantially U-shape and pivoted at its lower end upon a pin 30 carried by said slide bar. A substantially inverted U-shaped link 31 pivoted at its lower end as 15 at 32 upon the bars 9, passes through the lever 29 above the pivotal point of the latter.

Each of the movable stanchions 12 has a 20 rectangular latch 33 pivoted to it at its upper end, which latch engages over the shifting bar 27 and normally rests in an inclined groove or slot provided transversely 25 of the upper edge of said bar 27. Each of the latches 33 is preferably made of a single piece of wire bent to shape and at one end passed through an opening in the upper 30 end of the stanchion 12 and extended through an eye formed at the opposite end of the wire, the remaining end portion of the wire being bent backwardly away from the latch to extend parallel with and above 35 one of the bars 9. This end portion or stop is indicated at 34, and its purpose is to limit the upward movement of the latch 33 when the latter is disengaged from the bar, so that when the latch is released it will drop down upon the bar and become engaged in the slot when the bar is moved into proper position.

In Fig. 1 the stanchions are shown as in 40 closed position. To open them the lever 29 is moved to the left in the direction indicated by the arrow, whereby the lower end of the lever in moving to the right, will shift the bar 27 to the right carrying the 45 movable stanchions with it and thus moving the upper ends of the movable stanchions away from the stationary stanchions. A reverse movement of the lever will again close the stanchions. It will be noted that 50 when the device is in closed position the link 31 is beyond the pivotal point 30 of lever 29, so that the device cannot become accidentally unlocked, it being necessary in order to open the stanchions to forcibly 55 raise the lever 29 until the pivot point 30 has passed beyond the link 31. Any of the movable stanchions may be individually operated, so that if only one or two animals are to be handled it will not be necessary to 60 operate the whole device. So too one or more of the animals may be taken from the device while the rest of the animals are left undisturbed. Should any of the individual movable stanchions be open, when the bar 65 27 is shifted to open the remaining stanchions,

the latches of the already opened stanchions will drop into their respective slots so that when the bar is again moved to closed position, all of the stanchions will be carried with it.

Although I have described the preferred embodiment of my invention, I may desire to make such changes in the construction, combination, and arrangement of parts thereof, as do not depart from the spirit of 70 the invention and the scope of the appended claims.

I claim:—

1. A feed rack including a pair of spaced lower beams, spaced skids arranged transversely of, and supporting, said lower beams, a plurality of spaced stationary stanchions connected at their lower ends between said beams, a pair of spaced upper beams secured on opposite sides of the stationary stanchions near the upper ends of the latter, a slide bar arranged upon the upper ends of the stationary stanchions, guides carried by certain of said stationary stanchions for retaining the slide bar in position, a lever 80 pivotally connected at its lower end to the slide bar, a link pivotally connected with the upper beams at one end, and at its other end being pivotally connected with said lever above the pivotal point of the latter, a plurality of movable stanchions arranged each between a pair of the stationary stanchions, and pivotally mounted adjacent their lower ends between the lower beams, stops carried by the upper beams for limiting the movement of the movable stanchions toward the stationary stanchions with which they are associated, latches pivotally carried by the movable stanchions and engaging in slots 85 provided in said slide bar, said latches being pivotally connected at their lower ends to the slide bar, whereby to be retained in position to be engaged by the slide bar when the latter is moved in one direction or another, a plurality of partitions carried each by one of said stationary stanchions, a bowl support carried by the partitions, and a plurality of feeding bowls carried by the support each 90 between a pair of the partitions and equidistant from one of the stationary and one of the movable stanchions.

2. A feeding rack including a plurality of spaced stationary stanchions, means for supporting them, a plurality of movable stanchions arranged one between each pair of stationary stanchions, a sliding bar supported upon the stationary stanchions, means for shifting the sliding bar in one direction or another at will, latches carried 120 by the movable stanchions and detachably engaging said slide bar, a plurality of partitions carried each by one of said stationary stanchions, a bowl supporting means supported by the partitions, and a plurality of 125 feeding bowls carried by the bowl supporting means.

bowls carried by the bowl supporting means and arranged between the partitions.

3. A feeding rack including a plurality of spaced stationary stanchions, means for supporting them, a plurality of movable stanchions arranged each between a pair of the stationary stanchions, means whereby the movable stanchions may be shifted toward and away from the stationary stanchions at will, a plurality of partitions supported each by one of the stationary stanchions, a bowl supporting device carried by the partitions and providing a plurality of rings arranged between the partitions, and a plurality of bowls supported each by one of the rings.

4. A feeding rack including a plurality of spaced stationary stanchions, a plurality of movable stanchions arranged between the stationary stanchions, means whereby the movable stanchions may be shifted at will toward and away from said stationary stanchions, a plurality of partitions carried each by one of the stationary stanchions, said partitions having their outer edges beaded, a wire extended through the beaded edge of each partition, said wire being anchored at its upper end whereby to help support the partition, a bowl supporting device, bolts carried thereby and having their upper ends hook-shaped and engaging each through an opening in one of the partitions above the wire carried thereby, said bowl supporting

means providing a plurality of rings arranged between the partitions, and bowls supported each by one of the rings.

35

5. A feed rack including a plurality of stationary stanchions, a plurality of movable stanchions arranged between the stationary stanchions and movable toward and away therefrom, a plurality of partitions carried each by one of the stationary stanchions, a bowl supporting device comprising a channel iron returned upon itself and having its members at intervals bowed outwardly to provide rings, blocks arranged between the portions of the channel iron lying between the rings, means connecting the blocks with the channel iron, and bolts carried each by one of the blocks and provided with a hooked portion engaging one of the partitions.

45

6. A feed rack comprising a plurality of stationary stanchions, a plurality of movable stanchions adjustable toward and away from said stationary stanchions, a plurality of partitions carried each by one of the stationary stanchions, a bowl supporting device suspended from the partitions, and a plurality of bowls carried by the bowl supporting device between the partitions.
